UNITED STATES PATENT OFFICE.

DANIEL SULLIVAN, OF BANGOR, MAINE.

IMPROVEMENT IN HAND-HOLE STOPPERS FOR STEAM-BOILERS.

Specification forming part of Letters Patent No. 147,704, dated February 17, 1874; application filed December 26, 1873.

To all whom it may concern:

Be it known that I, DANIEL SULLIVAN, of Bangor, in the county of Penobscot and State of Maine, have invented certain new and useful Improvements in Hand-Hole Stoppers for Steam-Boilers; and I do hereby declare that the following is a full, clear, and exact description thereof, that will enable others skilled in the art to which it appertains to make and use the same, reference being had to the accompanying drawings and to the letters of reference marked thereon, which form a part of this specification, in which—

Figure 1 shows a section of the device as applied to a boiler; Fig. 2, a front view of my stopper.

Same letters show like parts.

The object of my device is to produce a simple and economical device for stopping the hand-holes in steam-boilers.

My stopper is intended to apply to round holes, which can be much more easily and cheaply cut than the oval holes generally employed. Moreover, it does away with the red lead and similar substances commonly used for rendering the joint tight, and packs upon the outside of the boiler entirely, instead of on the inside, as common, enabling the iron to be kept clean and smooth with greater ease, and securing a more perfect joint.

My invention will be understood by reference to the drawing.

At *a* is shown a portion of the boiler, having the hand-hole *b* therein. This is round, and slightly larger in diameter than the flange *d* on the stopper. The stopper consists of a plate, *c*, having annular flanges *d* *e* thereon, and a screw-bolt, *f*, projecting from its center. This plate *c* is oval or elliptical in form, its width, in its narrowest part, being slightly less than the diameter of the hand-hole, so as to permit its entrance by slanting it, and inserting one of its longer ends. An annular rim of flange *d*, nearly the full size of the hole *b*, and nearly or quite as thick as the iron of the

boiler, is formed upon the outside of the plate *c*, and fills the hand-hole, while the oval portions or lips *g* of the plate or stopper press against the inside of the boiler, and prevent its being drawn out. A second flange or rim, *e*, may also be advantageously employed, serving as a guide to the cup *h*, and assisting in packing the joint. Over the bolt *f* is placed a cup, *h*, annular in form, its sides preferably having openings therein for convenience in holding the stopper by the bolt when it is to be removed from the hole. Around the lower portion of this cup is an annular groove, *i*, in which a rubber ring, *j*, is secured, this ring being of sufficient size to cover the edges of the hand-hole. (See dotted lines, Fig. 2.) The bolt *f* projects through the upper portion of the cup *h*, and the plate or stopper *c* and the cup *h* may both be forced tightly against the boiler by screwing up a nut, *k*, on the end of this bolt.

When the flange *e* is employed, the ring *j* is jammed closely against the surface of the boiler around the hole—the surface of the flange *d*, the periphery of the flange *e*, and the inner surfaces of the groove *i* in the cup *h*, thus packing in four directions, and making an absolutely tight joint.

What I claim as my invention, and desire to secure by Letters Patent, is—

The plate or stopper *c*, sufficiently narrow for insertion in the round hand-hole *b*, and provided with lips *g* *g*, annular flange *d*, and screw-bolt *f*, either with or without the annular flange *e*, in combination with the cup *h*, annular packing-ring *j*, and nut *k*, substantially as set forth and shown.

In testimony that I claim the foregoing I have hereunto set my hand this 24th day of December, 1873.

DANIEL SULLIVAN.
